J. B. DRUMM

TOOL

Filed Sept. 25, 1926

FIG. 1.

FIG. 3.

Inventor

J. B. Drumm
By Horace R. Chaudler

Attorney

UNITED STATES PATENT OFFICE.

JOHN B. DRUMM, OF WINSLOW, ARIZONA.

TOOL.

Application filed September 25, 1926. Serial No. 137,798.

This invention relates to new and useful improvements in tools, and particularly to pliers.

One object of the invention is to provide a tool of this character which normally remains in open position, ready to be easily engaged with the work, and which will automatically open, when pressure is released from the handles of the tool.

Another object is to provide a tool of this character wherein the jaw members are adapted to be shifted to engage with large or small work, and wherein the automatic opening is properly associated with the tool, so that the jaws will open regardless of whether the pliers are adjusted for large or small work.

Other objects and advantages will be apparent from the following description when taken in connection with the accompanying drawing.

In the drawing:

Figure 1 is a plan view of one member of the pliers, showing the spring being shown in the recess.

Figure 2 is a plan view of the other member of the pliers, showing the spring receiving recess, the spring being omitted.

Figure 3 is a sectional view of the pliers, the parts being in assembled position.

Referring particularly to the accompanying drawing, 10 and 11 represent the members of the pliers, each including a handle portion and a jaw portion, represented, respectively by the numerals 12 and 13. In the pivotal portion 14, of each of the members 10 and 11 there is formed a circular recess 15, that in the member 10 being of slightly larger diameter than that in the member 11, for a purpose which will appear later herein. A pivot bolt 16 is disposed through the pivotal portions of the members 10 and 11, and passes through the centers of the said recesses. The opening in the bottom of the recess of the member 10 is elongated, as shown at 17, whereby to permit moving the members transversely of each other, as in this well known type of shiftable pliers. In the bottom of the said recess, adjacent one end of the opening 17, is a

small circular opening 18, which receives one angularly turned end of a coil spring 19, which is seated in the recesses, when the members 10 and 11 are properly secured together by means of the pivot bolt 16. In 55 the bottom of the recess of the other member 11, there is formed an elongated arcuate slot, shown at 20 as being concentric with the bolt opening 21, thereof, said slot receiving the other angularly turned end of the said coil 60 spring 19.

The normal tendency of the spring is to spread its ends apart whereby to exert pivotal movement on the members 10 and 11, so that the jaws will be yieldably held separated for easy and quick straddling of the work to be operated upon. Upon grasping the handles of the pliers, and moving them toward each other the jaws will be engaged with the work, and upon releasing the grip 70 on the handles, the spring will expand to move the jaws away from each other.

The slot 20 permits the end of the spring therein to move, when the members 10 and 11 are shifted, as when adjusting for different sized work, and whereby the action of the spring will remain the same.

What is claimed is:

1. A tool comprising a pair of pivotally connected members, each of the members 80 having a recess in its pivotal portion, one of the recesses having an arcuate groove in its bottom wall, and a spring seated in said recesses and having one of its ends anchored in the bottom of one of the recesses and its 85 other end movably engaged in the arcuate groove of the other recess, for normally and yieldably maintaining the members in open position.

2. A tool comprising a pair of pivotally 90 connected and laterally shiftable members each having a recess in its pivotal portion, the bottom of one recess having an opening, the bottom of the other recess having a slot, and a coil spring seated in the registered 95 recesses and having its ends engaged in the opening and slot, respectively.

In testimony whereof, I affix my signature.

JOHN B. DRUMM.
